Primary Examiner — Mehri F Bajoul

(57) **CLAIM**

I claim the ornamental design for a basketball training device, as shown and described.

DESCRIPTION

FIG. 1 is a front elevational view a basketball training device showing my new design;

FIG. 2 is a front perspective view thereof;

FIG. 3 is a right side elevational view thereof;

FIG. 4 is a left side elevational view thereof;

FIG. 5 is a top elevational view thereof;

FIG. 6 is a bottom elevational view thereof; and,

FIG. 7 is a rear elevational view thereof.

The broken lines in the drawings depict portions of the basketball training device that form no part of the claimed design.

1 Claim, 5 Drawing Sheets
